UNITED STATES PATENT OFFICE.

ANDREW W. REDIN, OF ROCKFORD, ILLINOIS, ASSIGNOR TO CLAUS G. PETERSON, OF ROCKFORD, ILLINOIS.

LOCKING MEANS FOR LASTS.

1,066,049.

Specification of Letters Patent.

Patented July 1, 1913.

Application filed September 28, 1911. Serial No. 651,676.

To all whom it may concern:

Be it known that I, ANDREW W. REDIN, a citizen of the United States, residing at Rockford, in the county of Winnebago and State of Illinois, have invented certain new and useful Improvements in Locking Means for Lasts, of which the following is a specification.

The object of this invention is to provide an improved means for locking a last on a support such as a spindle or shoe-tree.

In the accompanying drawings Figure 1 is a side elevation partly in section of a last and tree provided with a locking means embodying the features of my invention. Fig. 2 is an elevation of the tree and last separated. Fig. 3 is an end elevation of the tree.

The last 1 may be of any desired form, being herein shown as divided into two parts to form a heel piece 2 and the toe piece 3, said pieces being hinged together. In the heel piece 2 is seated a thimble 4 adapted to receive a tubular stud 5 mounted in the end 25 of the tree 6. The heel piece also has a recess 7 for the reception of a pin 8 fixed in the tree 6. The tree has a slot 9 extending into its interior, the tubular stud 5 being secured in an enlargement 9^a at the inner 30 edge of said slot. A lever 10 lies in the slot 9 and is pivoted upon a pin 11 secured in the inner end of the tubular stud 5 one end 10^a of said lever lying within said stud and having a projection, or hook, 12 thereon 35 adapted to extend through registering openings 13 and 14 in the thimble 4 and stud 5 to lock the last 1 to the tree 6. A portion 10^b of the lever 10 at the opposite side of the pivot 11 extends diagonally outward to the 40 edge of the slot 9 so that the outer end of said lever may be engaged to swing the lever and withdraw the hook 11 from its locking position in the openings 13 and 14. A recess 15 in the face of the tree 6 permits of 45 thus depressing the lever 10. A coiled spring 16 seated in the recess 17 in the tree 6 bears against the lever 10 and tends to hold the portion 10^b of said lever in its outermost position, in which position of the 50 lever the hook 12 projects through the openings 13 and 14.

In securing the last and the tree together the thimble 4 is brought into registry with the stud 5 and the last moved toward the 55 tree, the outer end of the thimble 4 engag-

ing the rounded outer edge of the hook 12 and moving said hook inwardly. When the hook reaches the opening 14 it snaps into locking engagement with the thimble 4, thus securing the last to the tree. 60

As will be observed, the locking means herein disclosed is strong and rigid, and at the same time is very simple, indeed, consisting of but few parts. The guiding means 4, 5, for properly positioning the last 65 with reference to the support, is put to the additional use of forming a part of the locking means.

I have herein described the invention as used for locking a last to a tree, but it will 70 be understood that the invention is equally applicable to securing the last upon a spindle or other support.

I claim as my invention:

1. The combination of a last having a 75 thimble seated therein, a support having a tubular stud adapted to enter said thimble, said thimble and stud having openings arranged to register, and a locking member carried by said support said member extending into said tubular stud and engaging in said registering openings for locking the last to the support. 80

2. The combination of a last having a thimble seated therein, a support having 85 a tubular stud adapted to enter said thimble, said thimble and stud having openings arranged to register, and a pivoted lever carried by said support, one end of said lever extending into said tubular stud and having 90 a projection adapted to enter said registering openings for locking the last to the support.

3. The combination of a last having a thimble seated therein, a slotted support 95 having a tubular stud adapted to enter said thimble, said thimble and stud having openings therein adapted to register, a pivoted lever in the slot in said support, one end of said lever extending into 100 said stud and having a projection adapted to enter said registering openings, the other end of said lever extending outwardly to the surface of the support, and means tending to hold said lever in its locking position. 105

4. The combination of a last having a thimble seated in its heel portion, a support having a slot therein and having a tubular stud lying in said slot and adapted to enter 110

said thimble, said thimble and stud having openings arranged to register, a pivoted lever lying in said slot, one end of said lever extending into said tubular stud and having a hook adapted to enter said registering openings, the other end of said lever extending outwardly to the face of said support, and a coiled spring seated in a recess in said support and bearing against the last mentioned end of said lever to hold said end in its outermost position.

5. The combination of a last having a V-shape recess between the forward section and the heel section thereof, of a support having a projection adapted to fit into said recess, the heel section of said last having

a socket therein, a relatively small tubular stud having one end seated in said support, the other end of said stud being adapted to fit snugly into said socket, and a lever pivoted in said support, one end of said lever lying in said tubular stud and having a projection adapted to interlock in said socket, the other end of said lever extending outwardly to the surface of said support to be 25 manually operated.

In testimony whereof I affix my signature in presence of two witnesses.

ANDREW W. REDIN.
